UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

MANIFOLDING SALES-BOOK.

1,243,695.

Specification of Letters Patent.

Patented Oct. 23, 1917.

Application filed November 19, 1915. Serial No. 62,271.

To all whom it may concern:

Be it known that I, EDWARD K. BOTTLE, a citizen of the United States, residing at Elmira, in the county of Chemung and State 5 of New York, have invented certain new and useful Improvements in Manifolding Sales-Books, of which the following is a full, clear, and exact description, such as will enable others skilled in the art to which 10 it appertains to make and use the same.

My present invention relates to a very simple form of salesbook employing original and duplicate sales slips, which can be manufactured cheaply and is adapted to 15 many situations where more expensive books could not be used.

To accomplish the purposes of my invention I provide a support of usual form, with a pad of sales-sheets which are bound 20 together at one end into a stub, each sales-sheet comprising an opaque original sales-slip and a translucent duplicate sales-slip connected to the original. Secured to the book is a manila "rest" or sheet a little 25 thicker than the ordinary sales-slips, which gives a stiff surface upon which to write, and is impenetrable to prevent marking through on the lower slips. By preference the upper surface of this rest is coated, as 30 by being carbonized, so as to afford a copying or transfer material, though a carbon sheet may be used instead. The latter is held in place by a suitable spring clamp, which also engages the ends of the sales- 35 slips where the original and duplicate are joined.

By the use of a carbon-carrying manila sheet as a rest, a rest is obtained which, while sufficiently impenetrable to prevent 40 marking, is yet sufficiently flexible to be readily inserted between the leaves.

In the embodiment shown in the accompanying drawing, a sheet of manila paper or other moderately stiff material is attached at an intermediate portion of its 45 length to the stub formed by binding together the ends of the sales-sheets near the weakened lines G'. The staples which secure the sales-sheets together will also secure the manila sheet to this pad of sales-sheets. Extending from the opposite ends 50 of this intermediate portion H² of the manila sheet, are other portions H¹ and H³, the former providing a cover portion, and the 55 latter a rest portion of impenetrative mate-

rial, both the cover portion and the rest portion being foldable relative to the intermediate portion into position above the pad and between the sales-sheets, respectively, as illustrated. In this wise a single integral 60 sheet of manila serves to provide the support, the cover and the rest. The line or hinge X whereat the cover folds relative to the intermediate portion H² at the stub end of the book, being a bend in the manila 65 sheet, and below the upper face of the stub L, readily provides for the accommodation of pads which may have been assembled slightly out of designed position relative to the manila sheet. Wherever the stub is 70 placed on this sheet, the sheet may be creased on a properly located line, for it will be observed that in this embodiment the manila sheet is not directly attached to either the rear or top face of the stub, but folds over 75 both of these faces. The part of the manila sheet between the sales-sheets, that is between an upper translucent slip of a sales-sheet and a lower slip of the next adjacent sales-sheet 80 forms an impenetrable rest which prevents the marking extending through to the other slips, and also adds a certain stiffness to the book, rendering writing more easy. In the form of book in which the duplicate is translucent, which is that preferred, the manila 85 rest lies below the translucent duplicate of one sales-sheet and above the opaque original of the next below it, and in this arrangement the upper surface of the rest may be carbonized, which is the preferred construction; though, if desired, a sheet of copying 90 paper of any kind may form the duplicating means and may be attached at one end to the rest and lie upon its surface. If the entire sheet should be opaque, the manila rest is 95 not carbonized and a copying sheet may be introduced between the two parts of the sheets in the common way.

This particular form of improved book can be made at very small expense, and with 100 it is unnecessary to provide rigid covers. Its operation will be obvious from the foregoing description.

The above described salesbook is simple, 105 cheap to manufacture and easy to assemble. It is also easy to change pads in the course of business. It is obvious that other arrangements could be used which would be substantially similar and would come within the scope of the claims.

Having described my invention, what I claim as new and desire to secure by Letters Patent is:

1. A manifolding salesbook comprising, in combination, a pad of sales-sheets, each sheet comprising an original sales-slip and a translucent duplicate sales-slip connected to the original, said sheets bound together at one end to provide a stub, a support of flexible material underlying said pad and portions of flexible material extending from the opposite ends of said underlying supporting portion to provide a cover and an impenetrative freely foldable rest respectively, said cover portion being hinged to said intermediate portion at the stub end of the book on a line below the upper face of said stub, and said rest having a coat of transfer material on the face which is uppermost when the rest is interposed between said sales-sheets.
2. A manifolding salesbook comprising, in combination, a pad of sales-sheets, each sheet comprising an original sales-slip and a translucent duplicate sales-slip connected to the original, said sheets bound together at one end to provide a stub, a support of flexible material underlying said pad and portions of flexible material extending from the opposite ends of said underlying supporting portion to provide a cover and an impenetrative freely foldable rest respectively, said

cover portion being hinged to said intermediate portion at the stub end of the book on a line below the upper face of said stub, and said rest having a coat of transfer material on the face which is uppermost when the rest is interposed between said sales-sheets.

3. A manifolding salesbook comprising, in combination, a pad of sales-sheets, each sheet comprising an opaque original sales-slip and a translucent duplicate sales-slip connected to the opaque slip, said sheets bound together at one end to provide a stub, an integral sheet of impenetrative paper having an intermediate portion underlying said pad and connected thereto, and cover and rest portions extending from opposite ends of said intermediate portion and foldable relative to said intermediate portion into positions above the pad and between said sales-sheets, respectively, and transfer material carried by said rest on the face thereof which is uppermost when the rest is interposed between said sales-sheets, said cover portion being freely foldable relative to said intermediate portion on a line adjacent the stub end of the pad and below the upper face of said stub.

In testimony whereof I affix my signature in the presence of two witnesses.

EDWARD KIRBY BOTTLE.
